US00D788936S

(12) **United States Design Patent** (10) Patent No.: **US D788,936 S**
(45) Date of Patent: ** Jun. 6, 2017

(54) **PACKAGING UNIT FOR SINGLE MEDICAL DEVICE**

(71) Applicants: **BAXALTA INCORPORATED**, Bannockburn, IL (US); **BAXALTA GMBH**, Glattpark (Opfikon) (CH)

(72) Inventors: **Nicholas John Schill**, Johnsburg, IL (US); **Patrick John Ryan**, Buffalo Grove, IL (US); **Stephan Delville**, Lessines (BE); **Ibrahim Cherkani**, Ath (BE)

(73) Assignees: **Baxalta Incorporated**, Bannockburn, IL (US); **Baxalta GmbH**, Glattpark (Opfikon) (CH)

(**) Term: **15 Years**

(21) Appl. No.: **29/556,523**

(22) Filed: **Mar. 1, 2016**

(51) LOC (10) Cl. **24-02**

(52) U.S. Cl.

USPC **D24/229**

(57) **CLAIM**

The ornamental design for packaging unit for single medical device, as shown and described.

DESCRIPTION

FIG. 1 is a top perspective view of the present packaging unit for single medical device;

FIG. 2 is a right side view of the present packaging unit of FIG. 1;

FIG. 3 is a left side view of the present packaging unit of FIG. 1;

FIG. 4 is a top view of the present packaging unit of FIG. 1; FIG. 5 is a bottom view of the present packaging unit of FIG. 1;

FIG. 6 is a front view of the present packaging unit of FIG. 1; and,

FIG. 7 is a rear view of the present packaging unit of FIG. 1.

The dashed lines depict environment or portions of the unit that form no part of the claimed design.

1 Claim, 5 Drawing Sheets
